FOLDED TISSUES AND DISPENSER
THEREFORDonald C. Taggart, Westfield, N. J., assignor to
The General Cellulose Company, Inc., Garwood,
N. J., a corporation of New Jersey

Application February 15, 1946, Serial No. 647,821

1 Claim. (Cl. 206—57)

1 This invention relates to a dispensing carton having a tear-out portion and containing a stack of sheets each of which is arranged in such a manner as to permit their individual withdrawal from the dispenser when the tear-out portion of the same has been removed.

One object of the invention is to provide a dispensing carton or container for sheets in which the type and location of the opening in the container is so combined with the folded arrangement of the sheets as to permit increased ease in withdrawing sheets from the container one at a time. Another object of the invention is to provide a simple and inexpensive form of packaged sheets which, both before and after removal of the tear-out portion of the container, is compact and readily adapted to easy handling. Other objects and advantages will appear as the description proceeds.

The invention will be better understood by referring to the accompanying drawings in which:

Fig. 1 is a perspective view of a filled, unbroken carton;

Fig. 2 is a perspective view of the carton showing the tear-out portion removed and the contents of the carton exposed;

Fig. 3 is an enlarged, end elevation of the stacked sheets showing their folded arrangement, only the top and bottom portions of the stack being shown;

Fig. 4 is a view similar to Fig. 3, but illustrating a modified folding arrangement of the sheets.

Generally speaking the carton may be of any known or desirable construction. In the form shown it is made of paper and comprises a blank folded to provide a top 1, bottom 2, sides 3, 4 and ends 5, 6. Preferably the top is integrally joined along its edges to the sides and ends, and the bottom is hinged at one of its edges to one side (not shown) while at its opposite edge it carries a flap which is sealed to the inside of the side 3. Appropriate flaps are provided on the sides 3, 4, one of which is shown at 7 (Fig. 2), which are turned inwardly thereof. Flaps are also provided on the bottom 2 and are sealed to the inside of the ends 5, 6, one of such flaps being indicated at 8.

A tear-out portion 9 is disposed in the top 1 and end 5 of the carton and is shown as extending transversely but not completely across said top and end and also as extending longitudinally of the container from a position on the top of the container adjacent the edge 10 common to said top and end, through said edge, to a position intermediate the edges of said end 5. The por-

tion or section 9 is substantially completely bounded by perforated lines. As shown, the section extends transversely across the top and end of the carton from the perforated line 11 adjacent one top side edge of the carton to the perforated line 12 adjacent the opposite edge of the carton. In the opposite or longitudinal direction it extends from the partially perforated, partially cut line 13 in the top of the carton to the perforated line 14 in the end of said carton. The lines 13 and 14 are each located adjacent the common edge 10 of the top 1 and the end 5. At certain places in its boundary the section 9 is completely severed from the carton, as indicated at 15, 16 and 17, to aid in tearing the section away from the carton. Upon removal of the tear-out portion an opening 18 is left in the carton, exposing the stack 19 of folded sheets 20. As seen in Fig. 2, each sheet is folded to form a plurality of longitudinally extending tabs or free edges 21, 22, 23 and 24, which overlap the same side of the sheet. The sheets are stacked in the container with their tabs facing the top thereof, and it will be seen that the opening 18 extends in a direction transverse to that of the sheets or tabs, so that only an end portion of the sheets and tabs thereon is exposed. Thus each sheet may be individually withdrawn from the container by grasping one of the partly exposed tabs of the uppermost sheet, while the remaining sheets of the stack are confined within the container.

The sheets may be folded so as to have any suitable number of tabs or free edges. Preferably, and as shown in Figs. 2 and 3, the sheets have four free edges. In the modified folding arrangement in Fig. 4 the sheet 25 has two free edges, 26 and 27. The sheets may be of single ply or multi-ply construction, the latter being the preferred form, as illustrated in Figs. 3 and 4.

The carton is packed by inserting the stack of sheets through one end thereof, and this end is then sealed in place so that the sheets will be accessible only by removing the tear-out portion.

As indicated above, and as shown in Fig. 2, the tear-out portion 9 may be completely detached from the carton, leaving the opening 18 through which the sheets are accessible. In this form the carton is particularly suitable for pocket or handbag use. The tear-out portion need not, however, be completely detached, but may be partially severed, as on three sides thereof, and left hinged to the carton on the fourth side, preferably along line 14 (Fig. 1). In this form the carton may be attached to a wall by using the hinged tear-out

portion as a hanger flap. If desired, the hinged tear-out portion or flap may also be folded back and underneath the carton so as to support the same in an easel-like arrangement.

In view of the foregoing description, the following is claimed:

A packaged stack of paper sheets consisting of a dispensing container and a stack of folded sheets adapted to be individually withdrawn from the container, said container having a section bounded by perforated lines and extending transversely across the top and one end of the container from a perforated line adjacent one edge of the container to a perforated line adjacent the opposite edge of the container, the section being partially severable from the container to form an opening therein and also to serve as a hinged hanger flap therefor; each sheet of said stack being folded to form four longitudinally extending tabs overlapping the same side of the sheet, the sheets being disposed in the

5 container with their tabs facing the top thereof, said section extending in a direction transverse to that of the tabs so that when the opening is formed in the container only an end portion of the sheets and tabs thereon is exposed, whereby each sheet may be individually withdrawn from the container by grasping one of the partly exposed tabs, the remaining sheets of said stack being confined within the container.
